(57) **CLAIM**

The ornamental design for a paper towel holder countertop with spray bottle, as shown and described.

DESCRIPTION

FIG. 1 is a front, right and top perspective view of a paper towel holder countertop with spray bottle showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the paper towel holder countertop with spray bottle, shown in condition of use;

FIG. 10 is an enlarged partial view of FIG. 1;

FIG. 11 is an enlarged partial view of FIG. 2; and,

FIG. 12 is an enlarged partial view of FIG. 3.

The broken lines in the figures illustrate portions of the paper towel holder countertop with spray bottle that form no part of the purpose of depicting the boundary lines of the enlarged view and form no part of the claimed design. Other dash dot lines illustrate environmental subject matter that form no part of the claimed design.
